APPARATUS FOR CUTTING PIPE IN A WELL

Filed Jan. 2, 1930

UNITED STATES PATENT OFFICE

ERNEST J. NICKLOS, OF PONCA CITY, OKLAHOMA, AND CHESTER A. RASMUSSEN, OF LONG BEACH, CALIFORNIA

APPARATUS FOR CUTTING PIPE IN A WELL

Application filed January 2, 1930. Serial No. 417,860.

Our invention relates to a sawing device, and relates particularly to a sawing device adapted to be operated from a remote point. Our invention has its particular utility where it is desired to saw off or sever members such as pipes or beams under conditions where the workmen cannot remain in close proximity to the member which is to be sawed. Illustrative of the utility of the invention, one instance of its use that may be cited is where an oil well was brought in under such high pressure as to break the Christmas tree or outlet piping loose from the upper end of the casing, the Christmas tree being thereafter held in position above the casing, and in the path of the flow of oil and gas from the well, by the outlet pipes which extend from the Christmas tree and are secured firmly to the derrick structure. The presence of gas and gasoline vapors in the derrick prevented workmen from remaining for any length of time on the derrick floor. By the use of our invention, we were enabled to saw through the outlet pipes by employment of manual power at a remote point, thus releasing the Christmas tree, so that it could be easily removed from the well. The removal of the Christmas tree left the space above the casing clear so that a capping device could be successfully applied.

It is an object of our invention to provide a sawing device which may be applied to a member to be severed and which may be actuated from a remote point. The invention is of especial utility where the member to be sawed cannot be approached or where persons standing near might be injured when the member is sawed.

A further object of the invention is to provide a sawing device which may be applied from a remote point to a member to be sawed, and which is adapted to be manipulated by a workman standing at a safe distance from the member to be penetrated.

A further object of the invention is to provide a sawing device having a novel means for securing and locking the saw blade thereon in operative position.

A further object of the invention is to provide a saw of the above character having an

operating means consisting partly of a non-flexible member and partly of a flexible member, together with a mechanical device for moving the handle in reverse direction.

Further objects of the invention will be made evident throughout the following part of the specification.

Referring to the drawings, which are for illustrative purposes only,

Figure 1 is a diagrammatic elevational view showing a use of the invention.

Fig. 2 is a partly sectioned enlarged elevation of the saw head of the sawing device.

Fig. 3 is a cross section on the plane represented by the line 3—3 of Fig. 2.

Fig. 4 is a cross section on the plane represented by the line 4—4 of Fig. 2.

Fig. 5 is a view corresponding to Fig. 2, partly sectioned as indicated by the line 5—5 of Fig. 2.

Fig. 6 is an outer end view of the saw blade employed in this embodiment of the invention.

In Figure 1 we show an oil well derrick 11 having a floor 12 in the center of which the outlet pipe or Christmas tree 13 is located. For the purpose of illustrating a utility of the invention, it may be assumed that the Christmas tree has become disconnected from the well casing indicated at 15, this disconnection

permitting gases to escape into the space above the derrick floor 12. In order to apply a cap or capping device to the casing 15, it is necessary to remove the Christmas tree 13, but owing to the presence of asphyxiating or poisonous gases within the derrick, it is impossible for workmen to disconnect the flanges between the Christmas tree and the outlet pipe or pipes indicated at 16. It will be recognized that should the issuing oil or

gases be burning, it would be practically impossible for workmen to approach the Christmas tree. By use of our sawing device 20, however, pipes or other members connected to the Christmas tree 13, for holding same in place, may be readily severed so that the Christmas tree may be removed.

The sawing device comprises a saw head 21 which includes a U-shaped frame 22 having a longitudinal bar portion 23, an upright

inner end bar 24 and an upright outer end bar 25, there being a handle connecting portion 26 extending rearwardly from the inner bar portion 24. In a slide 27 mounted on the upper face of the handle connecting bar 26 a block 28 is slidably mounted, this block 28 having a vertical slot in the forward end thereof to receive the rearward end 30 of a heavy saw blade 31, and having a laterally directed hole through which a pin 32 may be extended to hold the rearward end 30 of the saw blade 31 in the vertical slot of the sliding block 28. The outer end 33 of the blade 31 has a cross beam 34 mounted therein, as shown in Figs. 2 and 6, this cross beam 34 being adapted to enter a laterally directed bayonet slot 35 when the outer end 33 of the blade 31 has dropped into the vertical slot 36 in the upper end of the front vertical bar member 25. The rearward end of the handle connecting portion 26 is threaded as indicated at 37, so that one or more lengths of the pipe 38 may be connected thereto by use of a coupling 39, the pipe or pipes 38 forming a handle for operating the sawing device and forming part of the entire manipulating means of the sawing device.

Where permissible, such as where gases are flowing from a casing, as at 15, and a workman could stay within the immediate vicinity of the Christmas tree for a short length of time, or at least for the time existing between consecutive respirations, a workman, holding his breath or wearing a gas mask, may carry the saw head 21 in open condition, as shown in Fig. 2, into the derrick and place same over the pipe 16 which is to be severed. It will be perceived that the saw blade may be readily lowered from its position of full lines into a closed position with the cross beam 34 lying in the bottom of the bayonet slot 35. The locking lever 40 of the device may then be swung from its full line position to the dotted line position 41, this causing the cam end 43 of the lever 40 to move a connecting bar 44 rearwardly, in this instance, rightwardly, against the action of a spring 45 within the slide member or slide casing 27.

The connecting rod 44 is threaded through the rearward end of the slide block 28, thus causing the slide block to move rightwardly when the lever 40 is moved into the dotted line position 41. This rightward movement of the block 28 causes the blade 31 to be likewise moved in rightward direction so as to pull the cross beam 34 at the outer end thereof into the notch 46 at the lower end of the bayonet slot 35, thus locking the saw blade 31 securely in operative position. The block 28 may be of polygonal cross section if desired, but the same results may be accomplished by employing a member of round cross section, as shown in Fig. 4, and using in connection therewith a pin 48 adapted

to travel in a slot 49 so as to prevent rotation of the block 28 from the position in which it holds the blade 31 properly aligned with the slot 36 in the upper end of the front end bar 25. The extension handle represented by the pipes 38 is rested on suitable supports such as rollers 50 mounted on the upper ends of posts 51, and a mechanical actuating means 52 may be employed to move the sawing device in leftward or reverse direction, this mechanical actuating means consisting of a weight 53 attached to one of the pipes 38 by means of a rope 54 which is extended over a pulley 55 supported by a framework 56. The actuating means for the sawing device includes a rope extension 57 which may be pulled by one or more men, as indicated at 58. It will be recognized that the number of lengths of pipe which may be employed in the actuating means is limited, as there are certain limitations to the weight which one or more men may readily reciprocate, and there are also limitations placed thereon by the flexibility of the pipes 38. By use of the weight 53 to move the sawing device in leftward or reverse direction, we are enabled to manipulate the sawing device by a rope of any desired length, for in the operation of the device, the only operation to be performed by the workmen is to pull the sawing device in forward or rightward direction so as to produce a cutting action of the teeth 60 of the saw blade 31.

In the use of the invention, where workmen cannot approach the member to be sawed, the saw blade 31 is raised to open position and is frictionally held while the saw head 21 is advanced toward the device to be sawed by workmen standing at a required distance therefrom. When the head 21 is properly placed relative to member 16 to be sawed, a pull may be exerted on the lever 40 by means of a wire or cable attached to the perforated end 65, this causing the leftward end 66 of the member 27 to engage and force the saw blade downwardly out of the position in which it is frictionally held and so that the saw blade may then drop into closed position. After the cross beam 34 has dropped into the bayonet slot 35, the lever 40 may be pulled all the way over into the locking position indicated by dotted lines 41, thus causing the locking of the saw blade firmly in operative position, as previously described relative to the manipulation of the locking mechanism by use of the lever 40.

Although we have illustrated a practical and operative form of our invention, it is understood that parts thereof are representative of other parts, elements or mechanisms which may be employed to accomplish the identical results in substantially the same manner; therefore it is intended that the claims shall not be limited by the simplicity

of this disclosure but shall have the full scope of the following claims.

We claim as our invention:

1. A sawing device of the character described, including: a head frame adapted to receive a saw blade; an extended handle projecting from said head frame, whereby said head frame may be reciprocated from a remote position; means for holding said saw

10 blade in open position relative to said head frame to enable installation on a member to be cut; means associated with said head frame for closing and locking said saw blade relative to said head frame and means for operating said last mentioned means from a remote position.

2. A sawing device of the character described, including: a sawing head including a U-shaped frame and a blade adapted to close the open end of said frame, said blade having the teeth thereof facing inwardly relative to said frame, said sawing head being adapted for placement from a remote position around a member to be cut; an extended handle projecting from the rearward end of said sawing head; means associated with said sawing head for closing and locking said blade thereon; and means operated from a remote position for actuating said last mentioned means.

3. A sawing device of the character described, including: a U-shaped frame having a bayonet slot in the outer end thereof; a slide member longitudinally disposed on the inner end of said frame; a slide block operative within said slide member; a saw blade hinged to said slide block, said saw blade having an engager at its outer end adapted for engagement with said bayonet slot; and means for moving said slide block in a direction to produce locking of said engager in said bayonet slot.

4. A sawing device of the character described, including: a U-shaped frame having a bayonet slot in the outer end thereof; a slide member longitudinally disposed on the inner end of said frame; a slide block operative within said slide member; a saw blade hinged to said slide block, said saw blade having an engager at its outer end adapted for engagement with said bayonet slot; and means for moving said slide block in a direction to produce locking of said engager in said bayonet slot, said means including a cam connected to said slide block and a lever for operating said cam so as to produce the desired movement of said slide block.

5. A sawing device of the character described, including: a U-shaped frame having a bayonet slot in the outer end thereof; a slide member longitudinally disposed on the inner end of said frame; a slide block operative within said slide member; a saw blade hinged to said slide block, said saw blade having an engager at its outer end adapted for engage-

ment with said bayonet slot, said engager consisting of a cross beam having its ends extending laterally from said saw blade; and means for moving said slide block in a direction to produce locking of said engager in said bayonet slot, said means including a cam connected to said slide block and a lever for operating said cam so as to produce the desired movement of said slide block.

6. A sawing device of the character described, including: a U-shaped frame having a bayonet slot in the outer end thereof; a slide member longitudinally disposed on the inner end of said frame; a slide block operative within said slide member; a saw blade hinged to said slide block, said saw blade having an engager at its outer end adapted for engagement with said bayonet slot; and means for moving said slide block in a direction to produce locking of said engager in said bayonet slot, said means including a cam connected to said slide block and a lever for operating said cam so as to produce the desired movement of said slide block, said lever being adapted for manipulation from a remote position.

In testimony whereof, the said ERNEST J. NICKLOS has hereunto set his hand at Ponca City, Oklahoma, the 19th day of December, 1929, and the said CHESTER A. RASMUSSEN has hereunto set his hand at Los Angeles, California, the 14th day of December, 1929.

ERNEST J. NICKLOS.
CHESTER A. RASMUSSEN.
